UNITED STATES PATENT OFFICE.

ARNO DEBO, OF MANNHEIM-RHEINAU, GERMANY, ASSIGNOR TO INTERNATIONALE BERGIN-COMPAGNIE VOOR OLIE-EN KOLEN-CHEMIE, OF THE HAGUE, NETHERLANDS.

PROCESS AND APPARATUS FOR SPLITTING COAL, OILS, AND OTHER HYDROCARBONS.

Application filed May 15, 1925, Serial No. 30,555, and in Germany May 23, 1924.

It is already known that it is possible to hydrogenate and split coal, oils, and other heavy hydrocarbons so as to obtain therefrom readily volatile liquid products, such as benzine, petroleum and the like, by highly heating the initial materials with hydrogen under high pressure and condensing the products distilled off. In the reaction chamber pressures of 100 to 150 atmospheres and even more, and a temperature of about 300 to 500° C. prevail.

If solid raw materials, such as coal, are being treated, these are finely disintegrated, and stirred to a paste with a liquid medium, preferably another hydrocarbon, so as to enable the material to be forced into the high pressure chamber. The thicker the mass can be, the more fully is the capacity of the reaction vessel utilized. If liquid substances, such as mineral oils or other hydrocarbons, are to be hydrogenated and split, solid substances are added thereto, for example sorption media such as diatomite, coke ashes and the like, or alkaline earth oxides, oil shales or the like, for the purpose of preventing deposition and burning of asphaltic materials and separation of coke. Thus in all cases there is the problem of forcing a mixture of solid and liquid substances into a vessel in which a very high pressure prevails.

If the hydrogenating and splitting of the initial materials in the reaction chamber has taken place in the presence of hydrogen, the reaction products must then be continuously removed again from the high-pressure vessel. These products are condensable and non-condensable gases on the one hand and liquid and solid residues on the other hand. The separation thereof has hitherto been effected by drawing off the gaseous products from the highest point of the heated receptacles while the residues are drawn off at the lowest point. Certain disadvantages and difficulties are connected with this procedure.

A special difficulty with the method of working hitherto employed consists in the uncertainty of maintaining a definite liquid level in the closed high-pressure container, the interior is not accessible to observation. If the filling becomes too great, the action of

the hydrogen is incomplete. If the liquid level sinks too low, the mass is liable to be burnt.

Now the present invention relates to a new process for forcing the solid and liquid raw materials into the high-pressure vessel in the form of paste, and withdrawing the gaseous, solid and liquid products of reaction continuously from the high-pressure container in such a manner that a definite liquid level is always maintained in the interior of the container.

While the pumping in of thick liquids, even in the case of the abovementioned high pressures, hardly causes any difficulties, paste-like masses, which are no longer fluid cannot be forced into high-pressure vessels on a large scale without special precautions. the thicker the mass is, the larger must be the suction aperture of the press or pump, and in the case of stiff pastes it must be so large that the clearance spaces would assume excessive dimensions, as a result of which the useful effect attainable would be very considerably impaired.

This difficulty has hitherto been met by conveying such pastes by means of liquids under pressure. Even then however a mixture could not be made as thick as would be desirable because otherwise the liquid under pressure would penetrate into the stiff mass instead of driving the latter before it. On this account, when forcing in a coal paste, it was not possible to take more than 1.4 parts of pulverized coal to 1 part of oil.

According to the present invention these difficulties are removed by first compressing the mass to be forced into a low pressure, and then immediately further pressing into the retort under a high pressure. The elimination of the compressed liquid now makes it possible to convey 2 to 2.5 parts of powdered coal to one part of oil. This preliminary pressure is preferably effected by means of a worm conveyor. When working without such preliminary compression only a pressure of 1 atmosphere can be used for filling the pump chamber but now a pressure of 3 to 5 atmospheres for example can be used. This combination of a high-pressure press with a

worm conveyor therefore presents special advantages, because by means of the latter it is immediately possible to make the inlet apertures as large as may be desired, while on the other hand the disadvantage of such a worm conveyor namely its unfavorable mechanical efficiency, is not important, as out of the total pressure drop of, say, 150 atmospheres, only from 3 to 5 atmospheres, that is to say, one-fiftieth to one-thirtieth of the whole, is affected by this low efficiency, while by far the greater part of the work done is carried out in the cylinder of a press at high efficiency.

While provision is made in this manner for the continuous and certain supplying of the raw materials to the high-pressure container, the removal of the products of reaction at the other end of the reaction container is also effected in such a manner that no dangerous sinking of the surface level of the liquid can take place. For this purpose, no separate removal of the gaseous and of the liquid and solid reaction products takes place, but the whole mixture is drawn off together from the container, this being done at a position located between the highest and lowest points, for example through a dipping pipe which extends down to the level of the normal surface of the liquid. In order to be able to draw off the constituents in all three states of aggregation together at such a position, a thorough mixing up of the entire contents of the container is indispensable. Stirring would however in any case have to be resorted to in order to prevent any settling out and on account of the fundamental mixing. In view of the distinctive character of the hydrogenation a large contact surface must be presented to the hydrogen and a definite duration of the action must be allowed. That is also the reason why the withdrawal of all the constituents, including the excess hydrogen, should not take place at the top of the vessel.

The carrying out of the process will now be explained in reference to the accompanying drawing. In this drawing 1 denotes a worm conveyor provided with a bunker or hopper 2, which forces the paste to be supplied to a high-pressure vessel 12 into a pipe 3. The latter leads through valves 4 and 5 to a press cylinder 6, in which a piston 7 is reciprocated under the action of a hydraulic driving mechanism 8, also constructed as a press cylinder. By the motion of the piston 7 the paste forced into the cylinder is forced through further valves 9 and 10 into a pipe 11, which is connected with the high-pressure vessel 12 to be fed.

The necessary hydrogen is continuously pumped in by a pump 13. The reaction vessel 12 is provided with stirring mechanism having driving means 14, the object of which is to prevent the deposition of solid materials and thoroughly to mix up the gaseous, liquid

and solid substances that are to take part in the reaction. At the same time the stirring mechanism may also serve by suitable means to prevent mixing up in the longitudinal direction of the reaction vessel, and thereby ensure a sufficiently long duration for the reaction. Such means are for example the discs 15 fitted on to the stirrer, which extend almost throughout the cross section of the vessel, leaving only a narrow gap at the periphery. 75

The substances taking part in the reaction and the products arising therefrom flow gradually through the reaction chamber in its longitudinal direction and in this manner arrive at the outlet aperture, which is formed as an immersed or dip pipe 16 and through a pipe connected thereto and a throttle valve 17 into a collecting passage 18, in which separation of the liquid and solid products from the gaseous products takes place at atmospheric pressure. While the gases are flowing through a pipe 20 to a gasometer the liquid and solid parts are drawn off from time to time through a valve 21. The throttle valve 17 is so adjusted that the pressure in the reaction chamber, indicated on a pressure gauge 22, remains constant throughout the whole duration of the operation. 80

In the case of the process described, the liquid level in the reaction vessel remains constantly adjusted to the height of the discharge aperture. If from any cause it falls somewhat lower, as a result for example of a temporary disturbance of the pump 7, no idle running and burning can occur, because gas is only drawn off from the pipe 16 until liquid level rises again. If the dip tube 16 begins to become immersed in the liquid, a rise of pressure occurs in the apparatus owing to the new products produced, and this rise of pressure is indicated by the pressure gauge 22. This pressure is then reduced again by regulating the throttle valve 17, and the surface level of the liquid sinks back to the mouth of the dipping tube. 90

In addition to the advantages already indicated it may be mentioned that the separating of the individual reaction products after expansion to atmospheric pressure is even simpler, easier and more complete than in the high pressure vessel, as hitherto arranged. 105

What I claim is:—

1. A process for maintaining continuously a definite liquid level in the interior of a high-pressure chamber when splitting coal, oils and other hydrocarbons by heating these initial materials with hydrogen at a high pressure, consisting in converting said materials into a paste-like mass, compressing said paste-like mass to a pressure of a few atmospheres, and then forcing it into the high-pressure chamber, and subsequently drawing off the gaseous, liquid and solid products of 120 125

reaction together from said high-pressure container at a point located between the highest and lowest parts thereof.

2. An apparatus for maintaining a definite liquid level in the interior of a high pressure chamber when splitting coal, oils and other hydrocarbons by heating with hydrogen at a high pressure comprising a worm conveyer for compressing a paste-like mass to a pressure of a few atmospheres, a pump for forcing

the compressed paste like mass into the high pressure chamber a tube in the high-pressure chamber which dips down to a point intermediate the highest and lowest points thereof for drawing off the solid, liquid, and gaseous 15 reaction products together.

In testimony whereof I have signed my name to this specification.

ARNO DEBO.
